UNITED STATES PATENT OFFICE.

CHARLES S. CRICKMER, OF DALLAS, TEXAS, ASSIGNOR TO THE GUIBERSON CORPORATION, OF DALLAS, TEXAS, A CORPORATION OF DELAWARE.

PARAFFIN SCRAPER FOR WELL APPLIANCES.

Application filed March 3, 1925. Serial No. 12,887.

This invention relates to new and useful improvements in paraffin scrapers for well appliances.

In placing tubing catchers in well casings considerable difficulty is frequently encountered when the inner walls are coated with paraffin. Such a condition reduces the inner diameter and causes the weight of the catchers to move upward and set the slips.

The object of the invention is to provide a device which may be associated with the lower end of a tubing catcher or other well appliance for scraping off the paraffin as the device is lowered in the well casing.

A particular object is to provide a device having a central tubular support and an annular scraping member surrounding the support and provided with a reduced scraping edge.

A further object is to provide a scraper having a plurality of inclined ports for deflecting a fluid passing therethrough.

Another object of the invention is to provide a scraper made in two sections, whereby it may be clamped in place without disconnecting the tubing catcher from the tubing.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a side view of a device constructed in accordance with the invention and illustrated partly in elevation,

Fig. 2 is a plan view of the same.

Fig. 3 is a plan view of the clamp form of scraper,

Fig. 4 is an elevation of the same, one of the members being broken away,

Fig. 5 is a cross-sectional view taken on the line 5—5 of Fig. 3,

Figure 6 is a sectional view illustrating the inclined ports forming deflectors, and

Fig. 7 is an elevation of a tubing catcher equipped with a scraper constructed in accordance with my invention.

In the drawings the numeral 10 designates a central tubular member or sleeve having internal screw threads 11 at each

end. Around its upper portion the sleeve 55 is surrounded by a circular scraping collar 12. The collar preferably has a smooth outer surface extending vertically, but this is subject to variation.

An important feature of the collar is its 60 annular scraping edges or rims 13 at its upper and lower ends, formed by dishing the ends of the collar; whereby the collar is reduced to a narrow edge. In order that the fluid may freely pass the device, the collar is formed with a plurality of vertical 65 passages or ports 14 extending therethrough. These serve to allow the fluid to pass through the collar and also to break it up into small streams.

In using the scraper the upper end of the sleeve 10 is screwed onto the lower end of the lower tubing section 18, a tubing catcher, such as is shown in Fig. 7, and the lower end of the sleeve receives the tubing (not shown) below the catcher. The upper end of the sleeve supports the coiled spring 19 which sustains the weight 20. The collar 12 has a diameter slightly less than the inner diameter of the well casing. When the catcher is lowered in the well the lower edge 13 of the collar will scrape the paraffin from the inner walls of the well casing and thus permit the catcher to be moved down the well without tripping the weight 80 and slips. Also upon an upward movement the upper edge 13 will remove the paraffin coating.

In Figs. 3, 4 and 5, I have shown another form in which the device may be 90 made in two sections and fastened on the tubing immediately below the catcher. This form has the advantage of being applied without disconnecting the tubing and catcher. The sleeve 10' is made in two 95 semi-circular sections formed at each end with complementary ears 15 and fastened together by bolts 16 and nuts 17. Semi-circular collar sections 12' are provided intermediate the ends of the sleeve. The collar has scraping edges 13' and fluid passages 14'.

If it is desired either form may be made with the type of passages shown by the other form. Should a greater retardation of the 105 fluid be required the passages may be given an inclination as at 14^a in Fig. 6. This will impart a whirling motion to the fluid and

reduce the impact at the weight of the catcher, whereby said weight will not be dislodged.

Various changes in the size and shape of the different parts, as well as modifications and alterations may be made within the scope of the appended claims.

What I claim, is:—

1. The combination with a tubing catcher 10 having a resiliently supported actuating weight, of a paraffin scraper comprising, a central support, and a circular scraping member surrounding the support.

2. The combination with a tubing catcher 15 having a resiliently supported actuating weight, of a paraffin scraper comprising, a central support, and a circular scraping member surrounding the support, said scraping member having its edge reduced 20 for scraping the paraffin from the walls of a well casing as the catcher moves downward therein.

3. The combination with a tubing catcher 25 having a resiliently supported actuating weight, of a paraffin scraper comprising, a central support, and a circular scraping member surrounding the support, said scraping member having its upper and lower edges reduced for scraping the paraffin from 30 the walls of a well casing as the catcher moves downward therein.

4. The combination with a tubing catcher 35 having a resiliently supported actuating weight, of a paraffin scraper comprising a sleeve and a circular scraping collar surrounding the sleeve for scraping the paraffin from the walls of a well casing as the catcher moves downward therein.

5. The combination with a tubing catcher 40 having a resiliently supported actuating weight, of a paraffin scraper comprising, a

sleeve, and a circular scraping collar surrounding the sleeve, said collar having vertical fluid passages for scraping the paraffin from the casing and deflecting the fluid from the weight.

6. The combination with a tubing catcher having a resiliently supported actuating weight, of a paraffin scraper comprising, a sleeve, and a circular collar surrounding the 50 sleeve and having its upper and lower ends dished to provide annular scraping edges, said collar having vertical fluid passages for scraping the paraffin from the casing and deflecting the fluid from the weight.

7. The combination with a tubing catcher having a resiliently supported actuating weight, of a paraffin scraper comprising, a sleeve, and a circular collar surrounding the 60 sleeve and having its upper and lower ends dished to provide annular scraping edges, said collar having vertical fluid passages, the sleeve extending beyond the collar and having means for securing it in place below the spring and weight of the tubing catcher.

8. The combination with the slip actuating weight of a tubing catcher, of a member located below said weight having a scraping edge for removing paraffin from the casing when the catcher moves downward in said casing.

9. The combination with the slip actuating weight of a tubing catcher, of a member located below said weight and adjacent thereto having openings for deflecting a 75 fluid into a plurality of streams and permitting a downward movement of said member in advance of a downward movement of said weight.

In testimony whereof I affix my signature.

CHARLES S. CRICKMER.
